UNITED STATES PATENT OFFICE

2,443,681

ARM ADJUSTER

Bruce A. Hower, Gary, Ind.

Application June 27, 1945, Serial No. 601,781

5 Claims. (Cl. 27—1)

1

This invention relates to an arm adjusting or holding means for holding the arms of a corpse after the embalming operation so that the arms will be properly set prior to the time of rigor mortis.

An object of this invention is to provide an arm adjuster or clamping means which is adapted to engage beneath the body or cadaver with the latter resting on the undertaker's table and which after completion of the embalming operations is adapted to clamp the arms prior to the time that the latter become set in a predetermined position. It is well known that after a corpse has been worked upon by an undertaker, the limbs are adjusted and the corpse or cadaver is then left to set in the predetermined position. After this setting period has transpired the limbs will firmly remain in their set position and if the limbs are slightly moved they will return to their originally set position. It is, therefore, an object of this invention to provide a clamping means which is adapted to engage the two arms of the body and hold these arms in adjusted position at points above the elbows with the hands resting over the body so that the arms will be firmly clamped during the setting period.

A further object of this invention is to provide a device of this kind which is simple in construction and which can be disassembled for insertion beneath the body when the latter is resting on the table.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail end elevation of an undertaker's table having an arm clamping device constructed according to an embodiment of this invention mounted thereof,

Figure 2 is a plan view of the device partly broken away,

Figure 3 is a detail end elevation of the device,

Figure 4 is a fragmentary sectional view taken on the line 4—4 of Figure 2,

Figure 5 is a fragmentary sectional view taken on the line 5—5 of Figure 2,

Figure 6 is a fragmentary sectional view taken on the line 6—6 of Figure 2,

2

Figure 7 is a fragmentary sectional view taken on the line 7—7 of Figure 4,

Figure 8 is a fragmentary sectional view taken on the line 8—8 of Figure 5, and

Figure 9 is a fragmentary sectional view taken on the line 9—9 of Figure 6.

Referring to the drawings, the numeral 10 designates generally an undertaker's table structure including a top 11 carried by a standard 13. An arms adjusting or clamping means is adapted to engage on the upper surface of the top 11 and comprises an elongated bar or pipe 12, which is formed at one end with a right angular upstanding extension 14. The extension 14 is adapted to be inserted between the inner side of one arm and the adjacent side of the body and the bar 12 is adapted to be extended beneath the back of the body at a point where the upstanding bar 14 will be positioned slightly above one elbow of an arm.

A second upstanding bar or pipe 15 is adjustably carried by the bar 14 being threaded into one branch 16 of a T-shaped coupling 17. The coupling 17 is formed with aligned branches 18 and 19 which have smooth inner surfaces so that the bar 12 may freely slide therethrough. The coupling 17 is firmly secured in adjusted position along the length of the bar 12 by means of a set screw 20. A horizontally disposed supporting bar 21 extends laterally from the upright 14 and is threaded at its inner end into one branch 22 of an L-shaped coupling 23. The coupling 23 is provided with a bore 24 extending therethrough at right angles to the branch 22 and the bore 24 slidably receives the upright 14. A set screw 25 is threaded through the coupling 23 and engages the upright 14 so that the lateral extension 21 may be vertically adjusted with respect to the upright 14. The extension 21 has adjustably secured thereto a depending arm clamping member or bar 26. The bar 26 is threaded into one branch 27 of a T-shaped coupling 28 which is formed with unthreaded aligned branches 29 and 30. A set screw 31 is threaded through the coupling 28 and engages the bar or pipe 21, so as to hold the depending arm engaging member 26 in adjusted position lengthwise of the supporting bar 21.

In the use and operation of this adjuster, the upright bar 15 is initially removed from the horizontal bar 12 and the extension 21 with its coupling 23 is removed from the upright 14. The bar 12 is then inserted beneath the back of the body adjacent the shoulder blades and the upright 14 is extended between one arm and the adjacent side of the body. The upright 15 is

then mounted on the bar 12 being adjusted lengthwise of this bar and secured in adjusted position against the opposite arm of the body, so as to press this arm inwardly in its pre-arranged position.

The extension 21 is then vertically adjusted on the upright 14 and the arm clamping member 26 carried by the extension 21 is adjusted lengthwise of the bar 21 so that the clamping member 26 will engage the opposite arm at a point above the elbow in order to tightly clamp this arm prior to the setting period of the body. After the body has set in its adjusted position the arm clamping or adjusting device hereinbefore described may be removed by taking off the clamping member 15 and the supporting bar 21 and then withdrawing the integral members 12 and 14.

The exact configuration illustrated is regarded as optimum, but some of the desirable results inherent in this disclosure may be obtained by various slight modifications including some departure from the exact configuration shown, and it is therefore requested that the scope of the invention should be regarded as limited only by the terms of the claims.

What I claim is:

1. An arm holding means for a cadaver comprising a member for positioning beneath the cadaver, an upright arm engaging member carried by said first member, an upright bar carried by said first member engageable with a side of the torso oppositely from said first upright member, a second arm engaging means carried by said upright bar and extending from said upright bar and means adjustably mounting said second arm engaging means thereon.

15

20

25

30

35

2. An arm holding means as set forth in claim 1 wherein said first named member is elongated, and means adjustably mounting said first upright member on said first named member.

3. An arm holding means for a cadaver comprising an elongated bar for positioning beneath the cadaver, an upright bar integral with one end of said bar and engageable against one side of the torso, a second upright bar engageable with an arm of the cadaver, means adjustably mounting said second upright bar on said first named bar, a horizontal bar extending from said first upright bar, and a depending arm engaging member carried by said horizontal bar.

4. An arm holding means as set forth in claim 3 including means adjustably securing said horizontal bar on said first upright bar.

5. An arm holding means as set forth in claim 3 including means adjustably securing said depending arm engaging member on said horizontal bar.

BRUCE A. HOWER.
